US00D643427S

(12) **United States Design Patent**
McGoldrick et al.

(10) **Patent No.:** **US D643,427 S**
(45) **Date of Patent:** **** Aug. 16, 2011**

(54) **HARD DISK DRIVE CASE**

(75) Inventors: **Thomas O. McGoldrick**, Laguna Hills, CA (US); **Manuel B. Camarena**, Yorba Linda, CA (US); **Jane S. Poon**, Irvine, CA (US); **Maciej M. Brzeski**, Mission Viejo, CA (US); **Mario Kiang**, Fremont, CA (US); **Edward T. Johnson**, Livermore, CA (US); **Salvador O. Navarro**, Oakland, CA (US)

(73) Assignee: **Toshiba America Information Systems**, Irvine, CA (US)

(**) Term: **14 Years**

(21) Appl. No.: **29/375,795**

(22) Filed: **Sep. 27, 2010**

(51) LOC (9) Cl. **14-02**

(52) U.S. Cl. **D14/356**

(58) **Field of Classification Search** D14/300-302, D14/314, 348-358, 432, 496, 125, 240, 242, D14/299; D18/56; D10/65, 75, 78; D13/149, D13/162, 184, 199; D3/201, 273; 361/679.31-679.45; D5/4, 55, 58, 60

(57) **CLAIM**

The ornamental design for a hard disk drive case, as shown and described.

DESCRIPTION

FIG. 1 is a perspective view of a hard disk drive case showing our new design.

FIG. 2 is a top plan view thereof.

FIG. 3 is a bottom plan view thereof.

FIG. 4 is a side elevational view thereof.

FIG. 5 is a front elevational view thereof; and,

FIG. 6 is a rear elevational view thereof.

The broken lines are for the purpose of illustrating unclaimed portions of the hard disk drive case, and form no part of the claimed design.

1 Claim, 3 Drawing Sheets
